COMBINATION CAN OPENER, FUNNEL, AND
FLEXIBLE PIPE ATTACHMENT

Charles F. Bertschinger, Waterbury, Conn., assignor to The Scovill Manufacturing Company, Waterbury, Conn., a corporation of Connecticut

Application May 2, 1934, Serial No. 723,520

12 Claims. (Cl. 221—23)

This invention relates to liquid handling apparatus and more particularly to a combination can opener and funnel, the latter having a flexible tube attached to the spout thereof.

5 One object of this invention is to provide a device of the above nature in which the discharge spout projects up into the funnel and is provided upon its upper end with an adjustable cutting knife and a co-operating can rim engaging hook, 10 said knife being adapted to pierce a hole in the side wall of the can for emptying the contents thereof.

A further object is to provide a device of the above nature in which the flexible tube is 15 detachably secured to the pouring end of the funnel spout for the purpose of directing the poured contents in various directions to points which would otherwise be difficult or impossible to reach.

20 A further object is to provide a device of the above nature in which means are provided for holding the flexible tube detachably with its end in an upwardly bent position to catch the drainings from the funnel when it is suspended from a supporting hook or allowed to rest upon a flat 25 surface.

25 A further object is to provide a device of the above nature which will be simple in construction, inexpensive to manufacture, easy to assemble and manipulate, compact, ornamental in appearance, and very efficient and durable in use.

With these and other objects in view there have been illustrated on the accompanying drawings, two forms in which the invention may be conveniently embodied in practice.

35 In the drawings:

Fig. 1 represents a side elevation of the combination can opener, pouring funnel and flexible tube as it appears in use with certain parts broken away to show the interior construction.

40 Fig. 2 is a detached detail plan view of the expandable tie member for retaining the flexible tube in bent position when the funnel is out of use.

Fig. 3 is an enlarged fragmentary sectional view 45 of the bayonet lock collar for detachably connecting the tube with the end of the funnel spout.

Fig. 4 is a perspective fragmentary view of the end of the funnel spout, showing the bayonet locking groove.

50 Fig. 5 is a fragmentary perspective view of the funnel bowl showing the attached handle.

Fig. 6 is a sectional view similar to Fig. 3 showing a modified form of screw connection for attaching the flexible tube to the funnel spout.

55 Fig. 7 is an enlarged vertical sectional view

taken through the funnel bowl and adjustable can-opening knife.

Fig. 8 is a front view of the same.

Fig. 9 is a side view of the combination device as it appears when supported by the D-ring. 5

Fig. 10 is a side view of the same when supported by the apertured handle.

Referring now to the drawings in which like reference numerals denote corresponding parts throughout the several views, the numeral 10 indicates a funnel bowl preferably made semi-spherical in shape and formed with a flared bell-mouth flange 11 circumscribing its upper edge. 10

The body of the bowl 10 is provided with an 15 eccentric drifted opening 12 adapted to receive an elongated tapering spout 13, which projects upwardly through the funnel bowl 10 and extends slightly above the plane of the bell-mouth flange 11, the upper rim 14 of said spout being outwardly flared, as shown. 20

The axis of the spout 13 is located at an angle of approximately 30° from the vertical axis of the bowl 10, and said spout 13 is preferably joined to the bowl by means of a continuous fillet of 25 solder 15. (See Fig. 7.)

In order to puncture the can, which may be either cylindrical or otherwise, provision is made of a concave knife 16 which is detachably secured to the upper front end of the spout 13 and 30 is adapted to extend upwardly a substantial distance above the open flanged end of said spout 13. The knife 16 is preferably made of tempered steel and is "cupped" at its upper end 17 to present a pair of sharp cutting edges 18, 18 which intersect 35 at a sharp puncturing point 19.

The knife 16 is detachably and adjustably secured to the funnel spout 13 within the bowl 10 by means of a pair of clamping plates 20 and 21, positioned inside the spout 13 and outside the 40 knife 16 respectively, said plates being held together by means of a pair of headed screws 22, 22. The screws 22, 22 fit closely in suitable apertures 23 in the outside plate 21 and are loosely located in an elongated slot 24 in the lower part of the 45 knife 16. The ends of the screws 22, 22 are engaged in tapped holes 26, 27 in the inside plate 20.

The upper end of the outside plate 21 has an integral hooked lug 28, so formed and positioned that the rim 29 of a can 30 may be engaged thereby prior to the can-opening operation. The lug 28 constitutes a fulcrum, on which the can may be tilted rearwardly with sufficient leverage to cause the knife 16 to penetrate and cut a tongue 31 out of the side wall of the can 30 and bend 50 55

the same against the adjacent end cover of the can, leaving an unobstructed opening 32 through which the contents of the can may be emptied. (See Fig. 1.) It is to be noted that the can opening 32 is so cut as to lie in alignment with the flared open end 14 of the spout to permit the contents of the can to flow freely thereto.

By positioning the spout 13 at an angle relative to the vertical axis of the bowl 10, as previously described, the can 30 will be caused to lie in an inclined position with the sheared hole 32 extending downwardly when said can is forced back as far as permitted, it being understood that the spout will normally be substantially vertical when in use. It will thus be seen that the entire contents of the can will be discharged through the opening 32 into the funnel. A trough-like handle member 33 having an end aperture 33a is attached to the outside of the bowl 10 and projects outwardly substantially in the same plane of the upper edge of said bowl to serve as a support for the emptying can 30.

The size of the opening 32 sheared in the can 30 may be varied by adjusting the position of the knife 16 relative to the spout 13, which adjustment may be readily accomplished merely by loosening the screws 22 and moving the knife along the spout as desired. If any of the oil or other fluid contents of the can 30 spills over outside of the spout during the pouring operation, it will be caught in the bowl 10 of the funnel and drained back into the spout 13 through a plurality of holes 34 provided in said spout 13 adjacent the bottom of the bowl 10. (See Fig. 1.)

In case it is desired to conduct the contents of the can 30 to a point difficult to reach by the straight spout 13, such as the filler pipe 35 of an automobile crank case, provision is made of a flexible metal tube generally indicated by the numeral 36 which may be detachably fitted to the pouring end of said spout 13. The tube 36 is preferably made of a section of spirally wound metal hose 37, and as shown in Fig. 1, has its lower end provided with a ring-shaped nozzle 38. In the first form shown in Figs. 1 and 3 the upper end of the tube 36 is preferably fitted into an enlarged socket 39 formed in the adjacent end of a tubular attaching collar 40. The collar 40 is adapted to slip over the lower end of the spout 13 and is detachably locked thereupon by means of an inwardly projecting knob 41 positioned on the interior of said collar 40 adjacent the upper edge thereof, said knob being adapted to fit in a bayonet slot 42 formed in the lower end of said spout 13.

In order to retain the flexible tubing 37 with its end bent at any desired angle so as to prevent dripping after the can 30 has been emptied and the funnel has been removed from the filler pipe 35, provision is made of a flexible tie member generally indicated by the numeral 42 and including a section of "safety" chain 43, a helical expansion spring 44, and a pair of end pipe-engaging split rings 45 and 46. The ring 45 is connected to the spring 44 and is made of round stock having semi-circular ends 47 connected by a radially offset loop 48 to which the adjacent eye of the spring 44 is attached. The semi-circular ends 47 are adapted to have swiveling engagement in an arcuate groove 49 surrounding the intermediate portion of the collar 40.

The split ring 46 on the opposite end of the chain 43 is preferably made of square stock and is formed in a shape similar to the ring 45, i. e., having semi-circular clamping ends 50 connected by a radially offset loop 51 adapted to be joined

to the end of the chain 43. The end link 51 of the chain 43 which engages the loop 50 is soldered or otherwise held rigidly in place so as to lie in the same plane as the ring 46. By means of this construction, the gripping effect of the sharp interior corner of the square stock of the ring 46 upon the flexible tubing 37 is enhanced.

In order to support the funnel when not in use, a D-ring 52 is pivotally attached to the outside surface of the funnel bowl 10 by means of a vertical bail lug 53 spot welded thereto. (See Fig. 1.) The funnel may then be hung upon a projection such as a nail 54 by means of the D-ring 52 in the manner as shown in Fig. 9, in which case the flexible pipe 37 is bent upwardly as shown and retained in such position by sliding the flexible tie member 42 to the position shown, thus catching the residual liquid draining from the funnel and preventing it from becoming lost.

The funnel may also be supported as shown in Fig. 10, by hanging it upon a nail 55 engaging in the aperture 33a provided in the outer end of the bowl handle 33. The flexible tube 36 may then be flexed as shown in Fig. 10 and retained in this position by the flexible tie member 42.

In case the funnel is supported by the D-ring 52 with the flexible pipe 36 detached from the spout 13, said D-ring 52 is so positioned with respect to the center of gravity of the funnel that the axis of the spout 13 will lie substantially in a horizontal plane so that any liquid in the funnel will be caught in that segment of the bowl which is subtended by the dot and dash line 57 in Fig. 1.

The modified form of collar 58 for attaching the flexible pipe 36 to the end of the spout 13 as shown in Fig. 6 is similar in all respects to the collar 40 of the first form, with the exception that the upper part of the collar is provided with an interior thread 59 which is adapted to threadedly engage upon a pair of staggered outwardly projecting nubs 60 positioned upon the spout 13 adjacent the pouring end thereof.

While there have been disclosed in this specification two forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new and for which it is desired to secure Letters Patent is:

1. In a can-opening spout or funnel article, an open bowl, a tube extending through said bowl and sealed in the base thereof, and a cutter secured to said tube for piercing the side of a can, said tube having apertures above the base of said bowl to permit liquid to drain from said bowl to said spout, the top of said tube being located above the plane of the top of said bowl.

2. In a can-opening spout or funnel article, an open bowl, a tube extending through said bowl and sealed in the base thereof, and a cutter secured to said tube for piercing the side of a can, said tube having apertures above the base of said bowl to permit liquid to drain from said bowl to said spout.

3. In a can-opening spout or funnel article, an open bowl, a tube extending through said bowl and sealed in the base thereof, and a cutter se-

- cured to said tube for piercing the side of a can, said tube having apertures above the base of said bowl to permit liquid to drain from said bowl to said spout, the top of said tube being located above the plane of the top of said bowl, the center axis of said tube being disposed at an angle to the center axis of said bowl.
4. In a combination can opener and funnel, a tube, a V-pointed cutter and a fulcrum all rigidly connected together as a unit, said fulcrum being engageable by the rim of a can, and the relations being such that an opening will be pierced in the side of the can when said can is swung around the fulcrum, and means for permitting longitudinal adjustment of said cutter with respect to said tube and fulcrum to produce a variable size of cut in said can.
5. In a combination can opener and funnel, a tube, a V-pointed cutter and a fulcrum all rigidly connected together as a unit, said fulcrum being engageable by the rim of a can, and the relations being such that an opening will be pierced in the side of the can when said can is swung around the fulcrum, said cutter having an elongated slot near its lower end, and screw means passing through said slot for detachably clamping said cutter in adjusted position upon the exterior of the upper portion of said tube whereby a variable size of cut may be made in the side of said can.
6. In a combination can-opener and funnel, a tube for insertion in a receptacle, a V-pointed cutter having a flat lower end lying in contact with the exterior of said tube, a hooked fulcrum plate lying upon the outside of said cutter, an anchor plate located inside said tube behind said cutter and fulcrum plate, and screw means passing through said fulcrum plate, cutter, and anchor plate for detachably clamping said cutter in adjusted position with respect to said tube and fulcrum to produce a variable size of cut in the side of the can.
7. In a combination can opener and spout, a tube open at both ends, a knife attached to said tube at the top thereof for puncturing the side of a can, a fulcrum fixed adjacent said knife and adapted to be engaged by the rim of a can to cause an opening to be pierced in the side of said can when said can is swung about said fulcrum, a funnel bowl surrounding said tube in liquid sealing relation to receive liquid which spills therefrom, and a laterally extending member secured to said bowl to support said can when swung down to pierce the opening therein, said member also serving as a handle for manipulating said spout.
8. In a combination can opener and funnel article, a funnel bowl, an upwardly extending cutter rigidly supported with respect to said bowl, a fulcrum member rigidly supported with respect to said cutter, and means for permitting said article to be suspended after it has been used so that liquid will not drip from said bowl but will remain in the side of said bowl.
9. In a funnel including a connected bowl and tube, a flexible pipe detachably joined to the lower end of said tube, a flexible and resilient chain fixed at one end to said tube and slidably and adjustably connected at its other end to said pipe, and means cooperating with said chain for holding the lower end of said pipe curved upwardly to prevent liquid from dripping therefrom when said funnel is hung up after it has been used.
10. In an attachment for a funnel having a connected bowl and tube, a flexible pipe detachably joined to the lower end of said tube, and means for adjustably holding said pipe with its lower end curved up to prevent liquid from dripping therefrom when said funnel and attachment are hung up as a unit after using, said means including a pair of split end clamps for engaging the exterior of said tube and pipe respectively, and a connected chain and a coiled spring located between said end clamps.
11. In a combination can opener and funnel article, a connected tube and bowl, a cutter knife and fulcrum unit rigidly supported above the base of said bowl, a flexible metal hose detachably connected upon the lower end of said tube to facilitate the delivery of liquid from said funnel to any desired location, a pair of hook members for use in selectively hanging said article in two different angular positions, and yieldable means for adjustably holding the lower end of said hose curved up to prevent dripping of liquid therefrom.
12. In a combination can-opener and spout, a tube open at both ends, a knife attached to said tube at the top thereof for puncturing the side of a can, a fulcrum fixed adjacent said knife and adapted to be engaged by the rim of a can to cause an opening to be pierced in the side of said can when said can is swung about said fulcrum, a funnel bowl surrounding said tube in liquid sealing relation to receive liquid which spills therefrom, and a laterally extending member secured to said bowl, serving as a handle for manipulating said spout.

CHARLES F. BERTSCHINGER. 55
